UNITED STATES PATENT OFFICE

THOMAS D. PRIDDY, OF CLEVELAND, OHIO, ASSIGNOR TO THE FORMED STEEL PRODUCTS COMPANY, OF CLEVELAND, OHIO

PLASTER BOARD

Application filed February 13, 1929. Serial No. 239,683.

This invention relates to an improved form of plaster board.

The object of the present invention is to devise a form of plaster board with an improved means of joining the plaster board sections at their joints both along the ends and sides thereof, the idea being to devise a means whereby even ordinary plaster may be used at such joints without danger of such plaster dislodging therefrom upon drying of the same.

Other objects will appear from the following description and claims when considered together with the accompanying drawings.

Fig. 1 is a partial front elevation of my improved structure; Figs. 2, 3 and 4 are sectional views taken on lines 2-2, 3-3, and 4-4, respectively, of Fig. 1.

According to the present invention, the sections of plaster board are secured to the metal studding 1 and the plaster board is of a form comprising a core 2 of plaster with the paper covering 3 extending over the two sides thereof. In the present case, the paper covering may be terminated at the edges of the core, as indicated in the drawings. It is to be understood that the sections of plaster board may be arranged in staggered relation with respect to their joints.

Heretofore, difficulty has been experienced because of the drying of the plaster or other binding material which is applied to the joints between the sections of plaster board, with the result that such plaster at the joints would crumble and fall out of the joints, thereby causing a considerable weakness and a very decided objection to such form of structure. This drying of the plaster at the joints has been due to the absorption of the moisture of such plaster by the core 2 of the plaster board. With the present arrangement, this objectionable feature has been removed.

As indicated in the drawings, the sections of plaster board are formed with spaced longitudinal dove-tail grooves 4 into which there is adapted to be applied the plaster which is generally used as a coating over the entire structure of plaster board sections after they have been placed in position. This

coating of plaster is indicated by reference numeral 5. These grooves 4 are so constructed and arranged that they will be substantially equi-distant apart and there will occur such a groove at the joint between two adjacent sections of plaster board, as clearly illustrated in Fig. 2. As will be apparent, the dove-tail form of groove tends to prevent the falling of the plaster from the surface of the plaster board and this advantage is especially important and valuable at the joints between the plaster board sections for reasons already referred to. That is, in spite of the tendency of the core of the plaster board to absorb the moisture of the plaster at the joints between the sections, the dove-tail form of groove which is provided at the joint, will prevent the plaster from falling out of the joint. Therefore, not only can the plaster be depended upon to remain in position between the abutting adjacent sections of plaster board, but furthermore, this present structure of joint makes it possible to employ various compositions of plaster which heretofore could not be used at all. The joint which is constructed in the manner just now referred to, is indicated by reference numeral 4a.

Another feature of the present invention consists in the beveling of the ends of the plaster board sections, as indicated especially in Figs. 3 and 4. That is, upon assembling the sections of plaster board, there will be provided a beveled groove between the adjacent ends of the sections with the result that the surface area over the edges of the ends of the plaster board sections is substantially increased and the efficiency with which the plaster adheres to these edges, is increased to a corresponding degree. That is, the ends of the plaster board sections are beveled in a direction transversely of the dove-tail grooves 4 and there is thus provided what might be considered an effective means of binding engagement about the end edges of the plaster board sections both with respect to the plaster in the dove-tail grooves 4 and also that which is applied to the main portion of the other surface of the plaster board sections. Those portions of the plaster board

sections which extend between the dove-tail grooves may be considered as ribs and although the layer of plaster over the surface of the ribs is considerably more shallow than the increased depth which is provided by the grooves 4, yet by virtue of the beveled end construction just now referred to and as especially illustrated in Figs. 3 and 4, the increased binding effect at the end joints, is effective in holding the plaster coating 5 in proper position over the surfaces of the ribs as well as within the grooves 4. Thus, there is a distinct cooperation between the beveling of the ends of the plaster board sections and the provision of dove-tail grooves which extend longitudinally of the sections. Furthermore, this cooperation is emphasized especially at the points 4a since both the beveling of the ends and the provision of the dove-tail grooves at the longitudinal joints serve as effective means for preventing dislodgment of the plaster from the joints. In other words, the combined effect which is produced by these two features in the present invention is most prominent at the point where the longitudinal and transverse joints meet. It is at this point that there is most need for such improvement as is provided by the present invention.

The present disclosure is merely for purposes of illustration, and various modifications might be effected without departing from the spirit of the present invention. For instance, the angle of the bevel on both the side and end edge portions of the plaster board may be varied. Also, the depth of the bevel groove on the end and the undercut groove along the side edges may be varied. The present invention may be embodied in various forms and compositions of plaster board or the like and the paper covering 5 may be arranged in various manners at the edges of the plaster board.

One of the principal advantages of the present invention resides in the dependable permanency with which the plaster or other binding material will remain in the joints as well as over the entire outer surface of the wall construction. Thus, the appearance is not marred by crumbling and dislodgment of the plaster from the joints, and the cost of repair is likewise reduced to a minimum. Another advantage consists in the possibility of using a form of plaster board or the like in which the covering 5 does not extend about the edges of the board. That is, practically any form of board can be used in an efficient manner with the present invention. This also means a reduction in cost.

Other advantages will be apparent to those who are familiar with the art to which the present invention relates.

What I claim is:

1. A wall board construction comprising a plurality of sections arranged with their ad-

jaacent edges in close proximity to each other, some of said edges being beveled so as to provide a joint space of increasing width from the bottom to the top of said joint, other of said edges being undercut from the surface of the section so as to provide dove-tail form of joint space, and binding material applied to said joint spaces.

2. In a construction of the class described, a section of plaster board or the like having one edge portion thereof continuously undercut with respect to and from the front surface of the plaster board so as to form part of a dove-tail groove through part of the thickness of the board to supplement a similarly formed edge portion of a companion section when assembled together.

3. A wall construction comprising a plurality of sections of plaster board arranged with their adjacent edges in close proximity to each other each section of the plaster board having a core of plaster and a covering therefor, said plaster board sections having the plaster cores thereof exposed at said edges, a plaster material applied to the joint space between the exposed plaster cores at said adjacent edges, so as to adhere thereto, and means for maintaining the same in set position in said joint space.

4. A wall construction comprising a plurality of sections of plaster board arranged with their adjacent edges in close proximity to each other, said edges being beveled so as to form a joint space of increasing width from the bottom to the top of said joint each section of the plaster board having a core of plaster and a covering therefor, said plaster board sections having the plaster cores thereof exposed at said edges, and a plaster material applied to the joint space between the exposed plaster cores at said adjacent edges so as to adhere thereto.

5. A wall board construction comprising a plurality of sections arranged with their adjacent edges in close proximity to each other, some of said edges being beveled so as to provide a joint space of increasing width from the bottom to the top of said joint, other of said edges being undercut from the surface of the section so as to provide dove-tail form of joint space, each of said sections having a core of plaster and a covering therefor, said sections having the plaster cores thereof exposed at at least some of the edges, and a plaster material applied to the joint space between the exposed plaster cores at said adjacent edges so as to adhere thereto.

In testimony whereof, I hereby affix my signature.

THOMAS D. PRIDDY.
